William H. Joyce, Pasadena, Calif., assignor to
 Pasadena Slipper Co., Pasadena, Calif., a cor-
 poration of California

Application June 27, 1936, Serial No. 87,783

4 Claims. (Cl. 36—2.5)

My invention relates to the art of making shoes, and has particular reference to a new and novel slipper construction and the method of manufacturing the same.

In the art of manufacturing shoes, particularly shoes of the type known as bedroom slippers, one or the other of two methods of construction have been employed; (a), the forming of an upper upon a last and attached directly to an insole member, to which is then attached an outsole member, usually formed of relatively stiff leather forming the outsole or tread portion of the slipper, the outsole being secured to the insole by suitable stitching at the edges of the soles, or, (b), the forming of an outsole of relatively thin and pliable leather having its edges upturned and sewed to the lower edges of the upper, with a layer of cushioning or packing material interposed in the cuplike outsole so formed, to thereby produce a soft-soled cushioned slipper.

In the first type of construction, the attachment of the upper directly to the outsole required the forming of a separate heel member to be attached to the outsole in order to provide the necessary heel lift for the slipper, while, in the latter type of construction the life of the slipper was determined by the thickness and wearing qualities of the leather of which the outsole is formed, and if a material of sufficient thinness and pliability to produce the necessary soft sole is employed, the wearing life of the slipper is relatively short. Moreover, the selection of the material to be used as the outsole covering would be limited to leather or a similar long-wearing material.

It is an object of my invention to provide a slipper of the character set forth wherein the slipper is formed of an upper which may be lasted and may be provided with an insole, if desired, an outsole which may be formed of relatively stiff leather, or similar material having a long wearing life, and a midsole interposed between the outsole and the upper which will provide the necessary and desirable cushioning effect and which may have the heel lift built directly therein.

Another object of the invention is to provide a slipper of the character set forth in the preceding paragraphs, wherein the midsole may be covered with any suitable material, such as cloth, permitting the employment of decorative colors on the midsole and upper to enhance the beauty and appearance of the slipper.

Another object of the invention is to provide

a slipper of the character set forth in the preceding paragraphs, wherein the beauty and comfort of a Chinese type slipper is obtained without either the discomfort of the flat sole and heel characteristic of such slippers, and in which the wearing sole of the shoe is formed as an additional and separate member, lending long life to the construction.

Another object of the invention is to provide a method of constructing a slipper, including an upper, an outsole, a midsole interposed between the upper and outsole, wherein the upper and midsole are secured together by adhesives, and the midsole and outsole are secured together by adhesives, thereby permitting the midsole to be covered by silk, satin or other relatively fragile material.

Other objects and advantages will be apparent from a study of the following specifications, read in connection with the accompanying drawings, wherein

Figure 1 is a side elevational view of a slipper, constructed in accordance with my invention;

Fig. 2 is a detail view of the midsole employed in the practice of my invention;

Fig. 3 is a perspective view of a loop of cloth or similar covering material which may be employed to cover the midsole member shown in Fig. 2;

Fig. 4 is a perspective view, illustrating the manner in which the cloth or similar covering may be applied to my midsole; and

Fig. 5 is an exploded view illustrating the manner in which the upper, the insole, the midsole with its cover, and the outsole may be assembled together in the practice of my invention.

Referring to the drawing, I have illustrated in Fig. 1 a slipper which includes an upper 1 which may be, and preferably is, formed over a last, such as is indicated at 2 in Fig. 5, and which may be constructed of cloth with or without stiffening material in the toe and counter. The preferred construction of the upper is to form the upper upon the last 2 and to stitch or cement the lower edges of the upper material to a suitable insole 3 by any of the methods or practices well known in the art of manufacturing shoes.

A midsole or cushioning member 4 may be constructed entirely separately from the upper and which is illustrated particularly in Fig. 2 as comprising a suitable cut shape of felt 5—(preferably cut to substantially conform with the shape of the sole of the desired finished slipper)—to

which is added a formed heel lift 6 which may also be constructed of felt.

As will be more apparent hereinafter, the primary function of the midsole member 4 is to provide a cushioning pad and a suitable lifting of the heel of the slipper to increase the comfort of the slipper and to satisfy these functions other materials than felt may be substituted, such as cork, fabricated rubber, or other fibrous materials 10 having the characteristic of both retaining its shape and providing resiliency or cushioning.

The slipper is also provided with an outsole member 1 which may be formed of thin leather or other material having the characteristic of long 15 wearing life, since this is the part of the slipper which is subjected to the greatest amount of wear during the useful life of the slipper.

By employing the relatively thick midsole 4 the outsole 1 may be formed from a flat sheet of 20 material, there being no necessity or desirability of providing any formed heel member for the outsole 1. Thus it will be observed that by constructing the slipper from an upper, a flat surfaced outsole member, and a midsole member 25 interposed between them which in itself provides the necessary heel lift and shaping of the foot-receiving portion of the slipper, all of the beneficial characteristics of a slipper having a formed heel are retained while at the same time all of 30 the manufacturing ease of a flat soled slipper are retained.

Further, by using the midsole member as hereinbefore described, the midsole member may be 35 covered with cloth, such as silk, satin or other delicate materials, permitting the use of harmonizing color schemes in the decoration of the slipper. For example, the upper may be covered with silk, satin or other cloth of one color, while the midsole may be covered with a similar cloth but 40 of a different color, harmonizing or contrasting with the color of the upper to present a pleasant, decorative appearance, and the outsole, which is employed, may be edged in black, brown, or any 45 of the other colors which are ordinarily employed upon the edges of leather soles, such latter color also being selected to harmonize with the color combination between the upper and the midsole.

The covering of the midsole may be accomplished in any desired manner, though I prefer 50 to form a loop of the covering material in the manner shown in Fig. 3, a strip of the material 8 having its ends sewed together as indicated at 9 to form a loop, the width of which will be sufficient to cover the edge surface of the midsole 4 with a 55 suitable amount of the material extending above and below the midsole to permit the same to be turned inwardly upon the upper and lower surfaces of the midsole, as shown in Fig. 4 wherein the edges 10 of the material are illustrated as being turned inwardly and cemented, or otherwise secured, to the surface of the midsole.

The midsole with its covering is then applied to the lasted upper and is secured thereto in any 60 suitable manner, though in view of the fragile character of the covering on the midsole, I prefer to cement the midsole to the upper, as by coating either the upper surface of the midsole or the lower surface of the insole, or both, with a suitable cement, using this adhesive as the sole 65 means of attaching the midsole to the upper. The outsole 1 may then be placed upon the midsole and secured thereto in any suitable manner, as by cementing the same to the lower surface of the midsole by suitable adhesive, such as described 70 for the attachment of the midsole to the upper.

If desired, the inside portion of the insole 3 may be covered with a suitable cloth lining 12.

It will thus be observed that I have provided a slipper construction wherein the upper may be made of any suitable material and may be 5 covered with silk, satin, or other relatively delicate cloth materials in suitable colors, and wherein a midsole forming the desired shape for the foot, and having the heel lift built therein, may be employed to present a flat lower surface to 10 which a flat wearing outsole may be attached and wherein the midsole lends itself to ready, harmonious decoration with the upper by permitting this insole to be covered with relatively delicate cloth coverings, forming pleasing color 15 combinations with the coloring selected for the upper.

It will also be observed that I have provided a ready method of constructing slippers of the character set forth, adapted both to ease of 20 manufacture and also adapted to permit the decorating of the slipper by the employment of cloth coverings for the upper and midsole members.

While I have shown and described the preferred 25 embodiment of my invention, I do not wish to be limited to any of the details of construction shown herein, except as defined in the appended claims.

I claim:

1. In a slipper construction, an upper, the lower 30 edges of which are turned inwardly and secured to the lower surface of an insole, a midsole member comprising a sole portion and a heel lift portion with a beveled upper face in contact with the sole portion, said midsole member being of relatively thick cushioning material having a substantially flat lower surface and shaped to extend completely over the lower surface of said insole, a covering of relatively thin material extending about the edges of said midsole member, 35 means for securing the upper surface only of said midsole member to the insole, and a substantially flat outsole member coextensive with said midsole member and attached solely to the lower surface of said midsole member. 40

2. In a slipper construction, an upper, the lower edges of which are turned inwardly and secured to the lower surface of an insole, a midsole member of increasing thickness from the rear of the forepart of the shoe to the heel end, and comprising a sole portion and a heel lift portion with a beveled upper face in contact with the sole portion, said midsole member being of relatively thick cushioning material having a substantially flat lower surface and shaped to extend completely over the lower surface of said insole, a covering of relatively thin material extending about the edges of said midsole member, means for securing the upper surface only of said midsole member directly to the lower surface of said 45 insole, and an outsole member coextensive with said midsole member and attached solely to the lower surface of said midsole member. 50

3. In a slipper construction, an upper, the lower edges of which are turned inwardly and secured to the outer surface of an insole, a midsole member comprising a sole portion, and a heel lift portion with an upper beveled surface in contact with the sole portion, said midsole member constructed of cushioning material 55 shaped to extend completely over the lower surface of the insole, a covering of relatively thin material extending about the edges of said midsole member and attached directly to the upper and lower surfaces of said midsole member, 70

means securing the upper surface only of said midsole member to said insole, and an outsole member co-extensive with said midsole member and attached solely to the lower surface of said midsole member.

4. In a slipper construction, an upper, the lower edges of which are turned inwardly and secured to an insole, a midsole member of relatively thick cushioning material shaped to extend completely over the surface of said insole and comprising a sole portion of substantially constant thickness

and a heel lift portion tapering in thickness toward the shank of the slipper to provide a substantially smooth lower surface to said midsole member, a covering of relatively thin material extending about the edges of said midsole member, means for securing the upper surface only of said midsole member to the insole, and an outsole member co-extensive with said midsole member and attached solely to the lower surface of said midsole member.
